COMBINED DRAWING TABLE AND LAMP THEREFOR

Edmund J. Robichaud, 1813 Stanley St.,
New Britain, Conn. 06053

Filed May 31, 1968, Ser. No. 12,143

Term of patent 14 years

Int. Cl. D6—01

U.S. Cl. D33—14

FIG. 2

FIG. 1

FIG. 3

FIG. 4

FIG. 1 is a front elevation perspective view of a combined drawing table and lamp therefor embodying my new design;

FIG. 2 is a right side elevation perspective view thereof; FIG. 3 is a rear elevation perspective view thereof; and FIG. 4 is a top perspective view thereof.

I claim:

The ornamental design for a combined drawing table and lamp therefor, as shown.
